[57] CLAIM

The ornamental design for a beverage dispensing head, as shown and described.

DESCRIPTION

FIG. 1 is a top, front and right side perspective view of a beverage dispensing head showing our new design, the broken line showing of a hose is illustrative of environmental structure only and forms no part of the claimed design.

FIG. 2 is a top plan view thereof;

FIG. 3 is a front elevational view thereof;

FIG. 4 is a right side elevational view thereof, the side opposite being a mirror image;

FIG. 5 is a rear elevational view thereof; and

FIG. 6 is a bottom plan view thereof.
